United States Patent Office

Des. 193,973
Patented Nov. 6, 1962

193,973

COMBINED REFUSE STORAGE AND TRANSFER BUILDING, OR THE LIKE

William A. Ferrari, Orin M. Anderson, and Robert L.
Smith, all of P.O. Box 6147, San Antonio, Tex.

Filed Mar. 16, 1961, Ser. No. 64,342

Term of patent 14 years

(Cl. D13—1)

FIGURE 1 is a side elevational view of a combined refuse storage and transfer building, or the like, showing our new design;

FIGURE 2 is a top plan view of the same; and

FIGURE 3 is an end elevational view of the same.

The other side and end of the building, not shown on the drawing, are like the side and end shown.

We claim:

The ornamental design for a combined refuse storage and transfer building, or the like, as shown and described.
